RESISTOR MOLDING APPARATUS

Herman L. Sklar, Coney Island, N. Y., assignor
to Micamold Radio Corporation, Brooklyn,
N. Y., a corporation of New York

Original application April 17, 1933, Serial No.
666,415. Divided and this application October
6, 1933, Serial No. 692,407

5 Claims. (Cl. 18—5)

The invention relates to the manufacture of electrical resistors wherein the terminals of the resistor are embedded within a mass of resistance material, and aims primarily to provide apparatus by which resistors of the above character may be economically and rapidly produced in large quantities. Certain of the features of the invention are particularly applicable to hot molded resistors, while others are also applicable to cold molding processes, as hereinafter explained in greater detail in the following specification which, taken in conjunction with the accompanying drawings, illustrates an apparatus adapted to be used in forming resistors in accordance with the invention, and certain steps or stages in such manufacture. In the drawings—

Fig. 1 shows a plurality of resistor terminals carried by a supporting and positioning strip adapted to be used as a part of the present invention.

Fig. 2 is a view similar to Fig. 1 but showing the terminals projecting toward the right of the figure coated with a low resistance material, which may be used to facilitate good electrical contact between the terminals and the resistance material proper.

Fig. 3 is a plan view of a resistor terminal supporting frame adapted to be used in carrying out the present invention, to support terminal holding strips of the character shown in Figs. 1 and 2, a portion of one of the plates forming part of such frame being cut away.

Fig. 4 is a bottom plan view of an upper main molding die adapted to be used in carrying out the invention, and indicating in dotted lines the operative position of the above mentioned frame in respect to such die.

Fig. 5 is a sectional view through said frame taken on the broken line 5—5 of Fig. 3, looking in the direction of the arrows.

Fig. 6 is a plan view of a main molding die adapted to be used in carrying out the invention.

Fig. 7 is a sectional view through a pair of main molding dies, with the resistor terminal carrying frame in operative position therebetween, and illustrating the position of the parts at the beginning of the molding operation.

Fig. 8 is a view similar to Fig. 7 but showing the position of the parts at the completion of the molding operation.

Fig. 9 is a fragmentary sectional view taken on line 9—9 of Fig. 8 looking in the direction of the arrows.

Fig. 10 is a longitudinal sectional view of a completed resistor unit.

The invention is illustrated as applied to the manufacture of electrical resistor units of the type illustrated in Fig. 10, having a main body portion of suitable resistance material 1 which may be of any suitable composition, for example, such as is known in the art having graphite, carbon black and iron oxide serving as conducting material, with a small percentage of high melting point wax, together with a binder consisting of phenol formaldehyde, resin and asbestos or other suitable inert filler. Various compositions suitable for the above purposes are well known in the art.

Wire terminals 2 are embedded within the resistance material 1 and usually project from the opposite ends thereof as shown in Fig. 10; preferably the terminals 2 are provided with enlarged heads 3 and I prefer also to provide the embedded ends of the terminals with a low resistance coating 4 in order to insure a noiseless contact between the terminal 2 and the main body 1 of the resistor. The low resistance coating 4 may be, for example, of a composition similar to the main body portion 1 of the resistor, but with an increased percentage of conducting material therein, or an alloy of low melting point may be employed, or a composition containing graphite and a suitable binder.

In forming resistors according to the invention in its preferred form, a series of resistor terminals 2 are placed in properly positioned alined recesses in a supporting strip 5 of tape-like character as indicated in Fig. 1, the heads 3 of the terminals projecting out sidewise from the strip. This strip 5 if desired may be of paper and may support the terminals in a manner similar to that employed for supporting pointed pins in common use, or a metal strip may be employed where a terminal support suitable for repeated use is desired.

Tape-like strips of the above character, carrying the terminals in proper position, may readily be obtained or produced in long lengths, usually in coil or roll form from which the desired lengths of strip may be cut off.

While the resistor terminals are supported as above described, their ends 3 may be readily coated to form the low resisting coating 4, as indicated at the right of Fig. 2, for example by dipping the ends of the terminals in a low resistance composition while properly supported by strip 5, or spraying the composition thereon. With a large number of terminals so accurately positioned and supported, the coating may be applied much more rapidly and accurately.

A suitable number of strips 5 carrying the terminals as aforesaid, are then ready to be placed in operative position between main molding dies 6 and 7, of the character shown in Figs. 6 to 9.

- 5 These dies are provided with opposed walls defining series of resistor shaped recesses 8, three parallel rows of such recesses being shown in Fig. 6, and at opposite ends of each recess 8 are provided grooves 9 adapted to receive the terminals 2, when the strips 5 are placed in proper position between dies 6 and 7.

I prefer to employ in connection with the strips 5 a holding frame of the character shown in Figs. 3 to 5, which is interposed between the main dies 6 and 7 during the molding operation. This holding frame may consist of a pair of plate-like members 10 and 11 detachably fitting together in definite relationship, dowel pins 12 in plate 11 being shown in Fig. 5 for this purpose, and fitting 20 in holes 13 in plate 10. The strips 5 may also be provided with holes 14 engaging pins 12, which locate the resistor terminals 2 accurately in respect to the holding frame, and the holding frame in turn may be accurately located in respect to the main dies 6 and 7, as by means of the holes 15 in the plates 10 and 11, which engage with the dowel pins 16 shown in Fig. 7 as mounted on the main die 7 and passing into dowel holes 17 in the lower main die 6.

- 30 In the illustrated form of the invention the plates 10 and 11 of the terminal holding frame are provided with openings 18, which line up with the resistor shaped recesses 8 when the holding frame is placed in operative position, the 35 walls of the plates adjacent said openings 18 serving to hold the terminals 2 and their supporting strips 5 securely in position. The opposed walls of the main dies 6 and 7 are provided with interior depressed portions 19 and marginal 40 depressed portions 20 adapted to receive the holding frame constituted by the plates 10 and 11, when the dies are forced together into the position shown in Fig. 8. This construction of the dies 6 and 7 leaves lands 21 surrounding the resistor shaped recesses 8, and the terminal receiving 45 grooves 9 are formed in these lands.

Preferably the holding frame comprised of plates 10 and 11, and the terminal supporting strip 5 are used in conjunction as above described, 50 for the purpose of properly and securely positioning the resistor terminals in the mold, but it should be noted that the strips 5 may be employed alone for the above purposes, although when used conjointly with the frame they will better insure 55 that the terminal strands are properly held and afford greater facility in handling.

- In forming resistors according to the present invention a plurality of "pills" or blocks 22 (Fig. 8) of suitable resistance material may be first 60 placed in recesses 8 of main die 6, suitable means for rapidly performing such an operation being known in the art and accordingly not described in detail herein. A suitable number of terminal supporting strips 5 (the heads 3 thereof being 65 preferably first coated with a suitable material 4), will then be placed in engagement with the dowels 12 of plate 11 of the holding frame. In the use of the illustrated forms of main dies 6 and 7, it will be noted that the terminal strip 5 shown in Fig. 1, containing only a single series of terminals projecting from one side thereof, is suitable for use at the opposite side edges of the main dies, while the supporting strip 5 shown in Fig. 2, which is provided with two series of resistor terminals in staggered relation and with

their ends projecting from opposite sides of the strip, is suitable for positioning in the intermediate recessed portions 19 of the main dies, one such strip 5 thereby serving both rows of resistor shaped recesses which are located on opposite sides thereof. 80

After the strips 5 have been properly positioned on plate 11 as above described, the plate 10 may be placed in proper relation to the plate 11 and the resistor terminal holding frame thereby constituted may be placed in proper position relative to the main dies 6 and 7, by engagement of holes 15 in the holding frame with dowels 16 of main die 7. In the illustrated form of the invention screws 23 (Figs. 3, 5 and 9) pass through the plate 10 of the holding frame and holes 24 in plate 11 into the main die 7 thereby detachably connecting the terminal holding frame to main die 7. 85 90

The illustrated die construction is adapted to be used in a hot molding process, the dies 6 and 7 being heated in such manner that the pills or blocks 22 of resistance material are quickly softened when placed in position, the result being that when pressure is applied to force the dies together from the position shown in Fig. 7 to 100 that of Fig. 8, the resistance material 1 readily flows in recess 8 in such manner as to completely surround the heads 3 of terminals 2, and embed the latter therein. It should be understood, however, that many of the features of the invention are also applicable to cold molding processes. The hot molding process, however, produces a resistor having a glaze which affords a substantially moisture impervious surface. 105

After the molding operation has been completed 110 and main dies 6 and 7 separated, the holding frame constituted by plates 10 and 11 carrying the completed resistor units may be detached from die 7, and plates 10 and 11 separated to allow removal therefrom of the completed resistor units, which are then supported by the strips 5. Subsequent handling of the resistors is much facilitated by having a large number of them supported in the above manner. 115

This application is a division of my prior application Serial Number 666,415, filed April 17, 1933 entitled Method of and apparatus for forming resistors. 120

While a specific apparatus and mode of procedure have been described above, it should be 125 understood that many changes may be made therein without departing from the essentials of the invention as set forth in the appended claims.

I claim:

1. A molding apparatus of the class described, including mating main dies defining a row of resistor-shaped recesses, and tape-like strips interposed between said dies and respectively disposed along opposite sides of said row, each of said tape-like strips having means spaced along the length thereof for supporting a plurality of resistor terminals in position to project laterally therefrom into the respectively adjacent recesses of the dies. 130 135

2. A molding apparatus of the class described, including mating main dies defining a row of resistor-shaped recesses, a resistor terminal holding frame detachable from and adapted to fit between said dies, said frame comprising separable plates having openings therein adapted to line up with said row of recesses and said frame being provided with means adapted to hold resistor terminals in position between said plates with their ends projecting into said recesses. 140 145 150

3. A molding apparatus of the class described, including mating main dies defining a row of resistor-shaped recesses, a resistor terminal holding frame detachable from and adapted to fit between said dies, said frame comprising separable plates having openings therein adapted to line up with said row of recesses and tape-like strips located between said plates having means spaced along the length thereof for supporting a plurality of resistor terminals in position to project laterally therefrom into the respectively adjacent recesses of the dies. 80
4. A molding apparatus of the class described including mating main dies defining a plurality of spaced rows of resistor-shaped recesses, and tape-like strips interposed between said dies and respectively disposed between said rows of recesses and along the outer sides of the outer rows of said recesses, each of said tape-like strips 85 having means spaced along the length thereof for supporting a plurality of resistor terminals in position to project laterally therefrom into the respectively adjacent recesses of the dies. 90
